(57) CLAIM

The ornamental design for a medallion for a golf club, as shown and described.

DESCRIPTION

FIG. 1 is a perspective view of our new medallion for a golf club;

FIG. 2 is another perspective view thereof; and,

FIG. 3 is an elevational view thereof.

The portion of the iron shown in Phantom does not form any portion of the present invention.

1 Claim, 1 Drawing Sheet

FIG. 3
